UNITED STATES PATENT OFFICE.

FRANCIS C. GOFF, OF ENGLEWOOD, ILLINOIS.

COFFIN.

SPECIFICATION forming part of Letters Patent No. 321,433, dated July 7, 1885.

Application filed May 17, 1884. (No model.)

To all whom it may concern:

Be it known that I, FRANCIS C. GOFF, a citizen of the United States, and residing at Englewood, in the county of Cook and State of Illinois, have invented a certain new and useful Improvement in the Manufacture of Coffins, which is fully set forth in the following specification, reference being had to the accompanying drawings, in which—

10 Figure 1 is a plan view of a coffin with my improvement; Fig. 2, a detail section of the same on the line xx , Fig. 1. Fig. 3 is a detail section of same on the line dd , Fig. 1, showing head-rest in perspective. Fig. 4 is an enlarged 15 side elevation of the lifter-stop. Fig. 5 is a detail section of head-rest on the line zz , Fig. 3. Fig. 6 is a detail section showing construction of false bottom, taken on the line yy .

20 My improvement relates to coffins so arranged that the body, after being placed in the coffin, may be raised and posed as desired for the purpose of showing the corpse.

I will now proceed to fully explain my invention, reference being had to the drawings herewith, and which form a part of this specification. In order to accomplish this purpose I either use a false bottom, which is placed in a coffin of the common form and pivoted to it at or near its foot, or else I so arrange a coffin 30 of the usual construction that the bottom may be used in the same manner as the false bottom. I will first explain the construction of a coffin with a false bottom. A frame, B' , similar in shape to that shown in the drawings, made of 35 light cast-iron or other suitable material, is attached to a coffin of the common form. This frame may be made, as shown in the drawings, with iron ribs R and a canvas bottom, P . By the construction of this frame, as shown, the 40 body lies down into the frame, and so there is no appreciable room lost by the use of this false bottom, and the casket need not be of unusual depth. The foot of this frame is hinged to the bottom of the coffin by suitable hinges, 45 h , or the frame may be pivoted to the sides, near the foot. When the body is in the coffin it may be raised to any desired incline by lifting the false bottom by means of the handles F . The struts I , which are pivoted to the 50 frame B' by the pivots v , will gradually incline toward a vertical position. When the body is inclined as desired, the handles are turned

so as to bring the stops H in such position as to engage the struts and the frame. The stops are rigidly affixed to the lifter-handles and 55 turn with them. One side of the stop is made with a lip, which is turned down and engages the teeth of the rack R when the stop is in position to engage the strut and the frame. The shank of the lifter-handle is made somewhat longer than the thickness of the casting, and is furnished with a nut, p , at the lower 60 end. This nut is not screwed tight to the frame, but is so adjusted as to give sufficient vertical play to the lifter to allow the stop 65 to be raised above the ratchet and moved backward and forward without engaging the teeth when the body is being raised or lowered; but the stop is brought down so as to engage the ratchet-teeth by the spring S when it is desired to hold it in place, and the handles are 70 released. Lugs or pins E are cast on the frame to prevent the struts from passing a vertical position.

When it is desired to lower the body, the 75 handles are lifted sufficiently to disengage the stops from the racks, the stops are then turned back, and the frame being gradually lowered the struts assume their original horizontal position. If it should be desired to use the bottom of the coffin itself, instead of a false bottom, the mechanism for raising and lowering 80 would be the same. It would, however, be necessary to raise the bottom B , Fig. 3, somewhat and allow it to rest on cleats, which would 85 also serve to prevent the struts from hanging down when the coffin should be raised from the ground.

In order to more completely pose the body I have provided the head-rest or pillow C , which 90 is pivoted to the frame B' on the line d . This head-rest is made with the countersunk seat k , in which the back of the head rests and by which the head is kept in position, and it may be raised or lowered and held in position by 95 any suitable device. I use a leg or pawl, m , which is hinged at one end to the head-rest by the hinge w , Fig. 5. The other end hangs loose, and when the rest is raised the pawl 100 will gradually incline toward a vertical position. There is a rack, q , over which this travels, and in which the loose end will engage, and so hold the head-rest in the position desired. When it is desired to lower the head-

rest, it is first raised slightly. The pawl is then pushed up against the lower side of the rest and held there while the rest is lowered to its normal position.

5 Having now fully described my invention, what I claim as new, and desire to secure by Letters Patent, is—

1. The combination, with the coffin-case A, of the false or supplemental bottom B, hinged 10 to the case A at the foot, and an adjustable support for the upper end of the latter, whereby the upper or head portion of the bottom may be adjusted and held at any desired height, substantially as and for the purposes set forth.

15 2. The combination, with the coffin-case A, of the false bottom B, composed of the frame B',

ribs R, and canvas bottom P, substantially in the form and for the manner and purposes set forth.

3. The combination, with the coffin-frame 20 A, of the bottom B, hinged thereto, the struts or supports I, pivoted to the said bottom, the handles F, the shanks of which extend loosely through the said bottom and carry nuts p, forming bearings for the depressing-springs S, 25 and stops H, attached to said handles and capable of engagement with the racks R', substantially as and for the purposes set forth.
